MEANS FOR REMOVING OR UNLOADING
BLOCKS, ETC.

Francis J. Straub, New Kensington, Pa.

Application February 11, 1952, Serial No. 270,936

7 Claims. (Cl. 214—1)

1

This invention relates to a method and means for removing or unloading blocks, bricks or the like, usually in cured condition, from racks in a more expeditious manner so that the operation may be carried out smoothly at least twice as fast as at present with half the men and thus without undue delays, and further to such a method and means whereby the racks may be unloaded in a manner much safer to the workmen in that the blocks may be exposed to the maximum extent for manual engagement and thus without offering hazards especially from above to free movement of the arms and hands of the workmen.

It is especially aimed to provide a means and method whereby the blocks or bricks may be removed from the standard or equivalent racks onto which they are delivered and retained while cured, in a single movement of a plunger or the equivalent.

Especially it is an object of the invention to provide in the procedure mentioned, means whereby the usual magnetically handled pallets will not be shoved or pushed off of the rack with the blocks incidental to the unloading of the blocks from the racks, and regardless of the capacity of the racks, even up to those which accommodate seventy-two blocks and even more under existing procedure.

Another object is to provide a method and means whereby the blocks or bricks may be pushed on to shelves or the like following which the shelves may be displaced one relatively to another so that the blocks or bricks thereon will be fully exposed especially from above, to the end that they may be better manually or by power means engaged and removed, the shelf from which the blocks or bricks are being removed thus being free of any shelf or shelves above the same or in the way of the hands and arm of the workmen removing a recognized hazard to expeditious operation, and one which frequently endangers the arms and hands.

It is also an object to provide a construction and method wherein the racks may be maintained either by a truck or independently thereof against tipping or any undesired movement incidental to the unloading of the blocks therefrom on to the shelves, and especially to provide means for latching the rack to a truck which carries pushing mechanism or to a stationary means or any equivalent.

More specific objects and advantages will become apparent from consideration of the description following, taken in connection with the ac-

2

companying drawings, illustrating an operative embodiment. In said drawings:

Fig. 1 is a view in side elevation illustrating the method and one form of the apparatus for carrying out the same;

Fig. 2 is a plan view of the apparatus shown in Fig. 1;

Fig. 3 is a vertical sectional view taken approximately on the line 3—3 of Fig. 2;

Fig. 4 is an enlarged elevation illustrating one form of means to retain the pallets on the racks during the pushing of the blocks or bricks therefrom;

Fig. 5 is a horizontal section taken on line 5—5 of Fig. 4;

Fig. 6 is a detail perspective of the mounting parts for one of the rotatable shelves;

Fig. 7 is a plan view illustrating an abutment or retainer for the pallets for use in unloading;

Fig. 8 is a side elevation of the abutment or retainer of Fig. 7;

Fig. 9 is a plan view of a modified form of shelf onto which the blocks may be pushed from the racks; and

Fig. 10 is a vertical section taken vertically and longitudinally on line 10—10 through the form of Fig. 9.

Referring specifically to the drawings, A represents a rack of the type which removably supports sheet iron pallets C which in turn support blocks or bricks B. Said pallets C while positioned in a block or brick press (not shown) have the blocks or bricks B deposited thereon, and the pallets C with the blocks or bricks thereon are removed from the press and deposited in the rack A. Rack A together with the pallets, blocks or bricks as a unit is portable and usually engaged and carried by a self-propelled truck and positioned within a curing oven, and after curing of the blocks and still as such unit carried by said truck to the yard or equivalent where the blocks or bricks are removed from the racks and arranged in piles. As shown, such rack A consists of a skeletonized metallic structure and comprises three channel-irons 10 at each side thereof to which are welded or otherwise fastened angle-irons 11 forming ledges for said pallets C. It will be realized that the racks are of usual skeleton form so as to be open at the ends and sides in order that the pallets may be removed and replaced, in practice usually by means of conventional magnetic lifting apparatus. The parts of the rack are suitably secured together and braced as by means of the bars or angles

13.

45

55 13.

Said rack A for instance is engageable by conventional forks on a self-propelled truck or the equivalent (not shown) which engage beneath the bars 13 or other suitable parts and move the rack and blocks as a unit to the yard. At the yard, said blocks B all at one and the same time are pushed onto shelves such as 14. The pushing of the blocks may be effected by any suitable mechanism, and for instance as shown, by a series of plungers 15, one above the other and mounted on a stationary means or carried by a truck or other self-propelled vehicle 16, such plungers 15 being rigid at the front of the truck or having a movement independently of the movement of the truck under control of the transmission of the truck or otherwise. As shown in Fig. 2, there is a plunger for each row of pallets C, and correspondingly there is one shelf 14 for each row of pallets C.

While the plungers 15 may be carried by and operated from a truck as described, it is to be understood that this is but one means of accomplishing the end in view since the plungers 15 may be arranged for hand operation by means of cam mechanism, a rack and gearing or may be reciprocated through any suitable source of power. The shelves 14 may be of various types, and as shown in Figs. 1, 2 and 6 may be rotatable shelves carried by a post 17, which may be stationary or capable of being moved from place to place and rigidly anchored in the ground or otherwise. On the post 17 the shelves 14 are rotatably mounted, having openings surrounded by depending collars or journals 18 which are supported and rotate directly on collars 19 rigidly fastened to said post 17. Said shelves as shown in Fig. 3 are adapted to be moved or swung from the position shown in full lines at the left to the position shown in full lines to the right. The movement of such shelves is individual and independently of each other so that after the blocks or bricks are shoved or pushed onto the shelves, any shelf independently of the others may be moved from full line position at the left in Fig. 3 to the full line position at the right in Fig. 3, or to an intermediate position wherein the blocks will be exposed and may be engaged manually by the workman or with power means without the dangerous hazard of having another shelf or shelves in the path of movement of the hands, arms, or working members of the body. One way of latching the shelves 14 in the position at the left in Fig. 3 is by having suitably located notches 20 in the collars 18 engage lugs 21 on the collars 19. It will be clear that the shelves 14 may be both rotated and freely slid or raised on the shaft 17 to facilitate the manipulation of the shelves.

According to the present invention, means are provided whereby the pallets will be retained in the racks, that is against sliding displacement along the ledges or angles 11 incidental to the pushing or removal of the blocks. Such means may be retainers or stops 22 (Figs. 4 and 5) welded to adjacent parts such as the channels 10, such retainers or stops between the channels being disposed in approximately the same plane as the pallets or at least not extending above the pallets.

It is to be understood that the pallets C with blocks or bricks B thereon are removed from the block machine or press. In accordance with my method, the blocks or bricks are removed end foremost from the pallets so that in the event bonds occur between the plastic of the blocks or

bricks and the pallets, or otherwise, any chipping of the blocks or bricks will be at the ends thereof rather than at the sides, which would be seen in a wall constructed of the blocks or bricks. To attain this end of pushing off the blocks from the pallets without also pushing the pallets from the rack A, the said stops or retainers 22 have been provided, it being clear that with the parts in operative position as shown in the drawings that while pushing of the blocks off of the pallets, said pallets will be held against movement relative thereto by abutting the racks at the stops or retainers 22. It is also desirable to hold the rack A against danger of tipping or overturning incidental to removal of the blocks or bricks, and to this end latches 23 have been provided. These latches are shown as of a type to be manually gripped and operated and may be of any desired number. As shown, a latch 23 is adapted to co-act at a notch 24 with flanges of end channels 10. The latches 23 are pivoted as by means of vertical pins 25 to arms 12 extending rigidly from a frame or guide 26 against which the rack A is placed or positioned prior to the unloading of the blocks or bricks therefrom. A contractile coil spring 27 is preferably attached at one end of each arm 12 and at the other end to a latch 23 in order to hold them in rack-securing position. Said frame 26 may be a part of and carried by the truck and for example be the frame of the operating mechanism for plunger 15.

As intimated, the racks A loaded with blocks B and their pallets C may be held against tipping over and the pallets C held against sliding from the pallets upon unloading by pushing the blocks off of the pallets, by a means independent of the truck or any pushing mechanism. This result is suggested in Figs. 7 and 8 and is accomplished without using the retainers 22. In these figures the rack A loaded with pallets C and blocks B is moved into abutment against upright angles D and an intermediate upright plate E, such angles and plate being anchored in the ground or otherwise. Said angles and plate are so disposed as is clear from Fig. 9, that they slightly extend across and abut the ends of the pallets C in order that as the blocks are pushed off of the pallets as by plungers 15 or any equivalent, the pallets cannot slide but the blocks will slide off of the pallets and between said angles D and plate E onto shelves 14 or any equivalent located in receiving relation thereto.

Various other changes may be resorted to provided they fall within the spirit and scope of the invention, and for instance I may use different types of shelving in lieu of the unit having the rotatable shelves 14. For instance, I may employ a type of slideable shelf as in Figs. 9 and 10. In this modified form of shelving there are slideable shelves 30 corresponding in number and arrangement to the shelves 14. Shelves 30 are slideable along angles or other ledges at 31 which are secured together in any suitable manner by an angle framework generally designated 32, and which includes upright parts 33 suitably anchored in the ground or otherwise held stationary. It will be seen that the shelves 30 are in operative position at the left in Figs. 9 and 10 to receive the blocks and that such shelves are adapted for manual engagement and individual movement to the right as shown by the dotted position of one of the shelves in Fig. 10 so that the blocks or 75 bricks thereon will be exposed and may be re-

moved by the workman without the hazards pointed out to his person.

It is to be understood that the terms "block" and "brick" have been used interchangeably or synonomously as the invention is equally applicable to the handling of ordinary brick, cinder building blocks, or even other analogous articles.

I claim as my invention:

1. In combination with a portable rack means having a brick-supporting pallet thereon, plunger apparatus operable to remove bricks from said pallet, means operable in response to relative positioning of said plunger apparatus, and portable rack means to maintain the latter in position against relative movement with respect to the plunger apparatus in the direction of and during the removal of bricks by the latter.

2. The combination of claim 1 having shelf apparatus to receive the bricks from the rack means.

3. The combination of claim 1 wherein one of said means includes structure to prevent removal of the pallet from the rack means during said removal of the bricks.

4. The combination of claim 1 wherein said rack means includes a stop member thereon disposed out of the path of removal of bricks and projecting into the path of removal of the pallet.

5. The combination of claim 1 including relatively stationary uprights, said uprights being of a height extending above the base of the pallet, and the space between said uprights being less than the width of the pallet.

6. In combination with a portable rack means having a brick-supporting pallet slidably disposed thereon, a plunger means operable to push bricks from said pallet, shelf apparatus to receive the bricks pushed from said rack means, latch mechanism carried by one of said means having parts to hold the rack means positioned against the plunger means to maintain the rack structure in position against relative movement with respect to the plunger means in the direction away from the latter during the removal of bricks by the plunger means, and one of said parts being movable so that the rack means may be engaged and released with respect to the plunger means.

7. The combination of claim 6 wherein said rack means includes a stop member to prevent removal of the pallet from the rack means during said removal of the bricks.
